DISPENSER FOR COLLAPSIBLE CONTAINERS

Harry Lingdell, Stratford, Conn.

Application July 19, 1946, Serial No. 684,659

8 Claims. (Cl. 222—95)

1

This invention relates to a dispensing device for use with collapsible tubes which may contain tooth paste, shaving cream, soaps, cosmetics, ointments and the like.

It has for its object to provide a means for dispensing the contents of a collapsible tube easily and conveniently, eliminating the necessity of removing the cap from the tube, squeezing the tube by hand, etc.

It has for its further object to provide an attractive container for the tube, thus eliminating the presence of unsightly tubes in medicine closets and the like.

It has as its additional object to provide a means for withdrawing all of the contents of the tube, which is thus more economical, since in squeezing the tube by hand some of the contents are frequently left in the tube.

With the foregoing and other objects in view I have devised the construction illustrated in the accompanying drawing forming a part of this specification. It is, however, to be understood the invention is not limited to the specific details of construction and arrangement shown, but may embody various changes and modifications within the scope of the invention.

In the drawing:

Fig. 1 is a front elevation of the device;

Fig. 2 is a vertical section taken substantially on line 2—2, Fig. 1;

Fig. 3 is a bottom view of the device;

Fig. 4 is a transverse section taken substantially on line 4—4, Fig. 1.

The device comprises a back or base 10, at the lower end of which is secured a base plate or head 11, having a seat 12 to receive the neck 13 of the collapsible tube 14. The seat 12 is lined with a bushing 15 composed of rubber or other suitable material, so the neck 13 will seat securely in the seat 12. The back may be formed from sheet metal or any suitable material.

At the upper end of the base 10 is a follower 16 provided with a transverse groove 17 to fit over the sealing cap 18 of the collapsible tube 14. The follower 16 has vertical sides 19 to strengthen the follower, and has a vertical rear wall 20, the vertical edges of which are bent inwardly to form vertical flanges 21, which slide in the vertical grooves 22 formed by turning over the vertical edges of the back 10. The vertical wall 20 is slit and the wall portions adjacent and on opposite sides of the slit are turned or bent forwardly to form a pair of lugs 23 to receive the pawl 24, which is pivoted between them at 24a. The lower end 25 of the pawl 24 is adapted to

2

engage the teeth 26 of a vertically slideable rack 27, which slides in a depression 27a in the base 10 and which when moved downwardly would thus cause the follower to move downwardly crushing the tube 14 between the follower 16 and the head 11. The teeth 26 of the rack have straight or horizontal lower edges and inclined upper edges for a purpose presently to be described.

10 The rack 27 is operated by a lever 28 mounted on a horizontal shaft 29 supported by the vertical sides 30 of the head piece 11. The sides 30 of the head 11 also furnish additional strength to the head 11. The shaft 29 is provided with a pin 31 in an opening 32 in the lower end of the rack 27 so that by pushing the lever 28 rearwardly the pin 31 will draw the rack 27 downwardly the distance between the teeth 26 or somewhat more, and thus pull the follower 16 down this amount to crush the tube 14 and force the contents of the tube 14 out through the circular opening 33 at the center of the seat 12 in the head 11. A tension spring 34 attached to the lever 28 and the head 11 automatically returns the lever 28 to its forward position when the rearward pressure by the operator is released. Bringing the lever 28 back to its forward position lifts the rack 27 and during this movement the lower end 25 of the pawl 24 slides 20 against the inclined upper surface of the rack teeth 26 so that it swings outwardly so as to slide by the teeth 26 on the rack 27. Thus the follower 16 is fed downwardly by a step by step movement through operation of the lever 28.

30 The opening 33 is normally covered by a closure 35 comprising a disc shaped portion 36 and an offset portion 37 pivoted to the head piece 11 at 38, Fig. 3, so as to swing the closure 35 horizontally back and from its position over the opening 33. The closure 35 is operated by a pin or lug 39 on the shaft 29 extending through a suitable opening 40 in the offset portion 37 of the closure 35, so that as the shaft 29 is operated by the lever 28 it first swings the disc portion 36 40 of the closure 35 away from its position over the opening 33 before the rack is drawn down to move the follower 16 to press the contents of the tube 14 out through the opening 33.

45 A cover 41 comprising a generally semi-cylindrical shaped member open at the bottom and at the one side is provided to completely enclose the tube 14, so the device is attractive when supported on a wall 42 by screws (not shown) through holes 43 in the base 10. The cover 41 is held in position by the spring action of its sides

43 which clamp against the head 11 and the side edges of the base 10. This cover acts as a container and guide or support for the collapsible tube to prevent its bending side ways out of position under pressure from the follower 16. It therefore keeps the tube central and in an upright position during the material feeding operation.

After the follower 16 reaches the limit of its downward movement and practically all the contents have been removed from the tube 14, the operator removes the cover 41, then lifts the handle 43 on the pawl 24, withdrawing the lower end 25 of the pawl 24 from the rack 27, so that it no longer engages the rack teeth 26. The handle extends outwardly of the pivot 24a so its weight normally holds the lower end of the pawl against the teeth of the rack. The operator then slides the follower 16 to its uppermost position, removes the collapsed tube and inserts a new filled collapsible tube 14. The cover 41 is then replaced and the device is ready for use.

It is to be noted that various size tubes may be used with the device, the only limits being that the tube must not be so long that it doesn't fit in the groove 17 of the follower 16 when the follower is in its uppermost position, and must not be of greater diameter than will fit in the device when the cover is in place. However, it is clear that collapsible tubes of shorter lengths and smaller diameters may be used without interfering with the efficiency of the device. The head or base 11 may be provided with openings 44 to receive the reduced or shouldered ends of guide rods 45 which form guides and holders for collapsible tubes of smaller diameter to hold them upright and prevent the tube buckling laterally under pressure of the follower. The follower 16 may also be provided with guide openings 46 for these rods. Also the follower may be provided with an upright lug 47 to carry a designation such as the word "empty" which will be visible through an opening 48 in the lower front of the casing to indicate when the follower reaches its lower position and the collapsible tube has been emptied, to thus notify the user to insert a new tube. This makes a sanitary, easily operated device for feeding paste from the tube to a tooth brush, shaving brush or other device, or to the hand if desired.

Having thus set forth the nature of my invention, what I claim is:

1. A dispenser for dispensing substances from a collapsible container comprising means for supporting the discharge end of the container, a follower adapted to press on the closed end of the container to force material from the discharge end, means for forcing the follower longitudinally of the container comprising a reciprocable toothed rack provided with ratchet teeth, a one way pawl carried by the follower cooperating with the rack for shifting the follower in a direction to compress the tube, a pivoted lever, and means operated by the lever to shift the rack to force the follower against the container.

2. A dispenser for dispensing substances from a collapsible container comprising means for supporting the container in an upright position with the discharge at the lower end thereof, a follower adapted to press on the upper end of the container to force material through the discharge, an upright reciprocable rack provided with ratchet teeth, a one way pawl on the follower cooperating with the rack to force the follower downwardly, a lever, a shaft operated by the lever, and a connection from the shaft to the

rack to reciprocate the rack and force the follower against the container.

3. A dispenser for dispensing substances from collapsible tubes comprising a support provided with a seat to receive the discharge nipple of the tube and support the tube and nipple in an upright position, said support provided with a discharge opening from said nipple, a follower adapted to press on the upper end of the tube to force the contents from the tube, means for forcing the follower downward with a step by step movement comprising a lever, an operative connection from the lever to the follower, a closure normally over the discharge opening and pivoted to swing substantially horizontally across the opening in the plane of the opening, and means operated by the lever to swing the closure from the opening prior to operation of the follower.

4. A dispenser for dispensing substances from a collapsible tube comprising a support including a tubular seat for the discharge nipple of the tube lined with a resilient lining of a size to retain the nipple, a pivoted closure over the lower end of said nipple mounted to swing across the discharge end of the nipple, a follower adapted to press on the upper end of the tube to force the contents through the nipple, an upright reciprocable tooth rack provided with ratchet teeth, a one way pawl on the follower adapted to cooperate with the rack to force the follower against the container, a shaft, a lever for operating the shaft, an operative connection from the shaft to the rack, and an operative connection from the shaft to the closure.

5. A dispenser for dispensing substances from collapsible tubes comprising a support provided with a seat to receive the discharge nipple of the tube and support the tube in an upright position, a follower provided with a transverse groove in its under side adapted to receive and form a seat for the closed upper end of the tube and press on the upper end of the tube to force the contents from the tube, means for forcing the follower downwardly with a step by step movement, a pivoted closure for normally closing the outlet from the nipple, and means operated by the follower operating means to swing the closure from the discharge nipple prior to operation of the follower.

6. A dispenser for dispensing substances from collapsible tubes comprising a support provided with a seat to receive the discharge nipple of the tube and support the tube in an upright position, an upright back member connected with said support, a follower adapted to press on the upper closed end of the tube to force its contents from the nipple, said back member being provided with laterally spaced upright guides for the follower and a guide channel between them, an upright toothed rack mounted in said channel in the back member, a pawl on the follower cooperating with the rack, a shaft in the support, an operative connection from the shaft to the rack, manual means for operating the shaft, and a cover open at the back to engage over the back member and enclosing the tube to support it laterally during the collapsing operation.

7. A dispenser for dispensing substances from collapsible tubes comprising a support provided with a seat to receive the discharge nipple of the tube and support the tube in an upright position, a follower adapted to press on the upper closed end of the tube to force its contents from the

nipple, means for forcing the follower downwardly to compress the tube with a step by step movement including a manually operable means, said support being provided with means for supporting a plurality of removable laterally spaced upright guide rods so located as to laterally support collapsible tubes of smaller diameters, and said follower being provided with guide openings to receive said rods.

8. A dispenser for dispensing substances from collapsible tubes comprising a support provided with a seat to receive the discharge nipple of the tube and support the tube in an upright position, an upright back member connected with said support and having its side edge portions formed with upright guide channels, a follower adapted to press on the closed end of the tube to force its contents from the nipple and provided with side flanges slidable in said channels, a vertically reciprocable toothed rack between said guide channels, said back member being provided

10
